UNITED STATES PATENT OFFICE

ALDEN M. DRAKE, OF GREENFIELD, MASSACHUSETTS, ASSIGNOR TO GREENFIELD TAP & DIE CORPORATION, OF GREENFIELD, MASSACHUSETTS, A CORPORATION OF MASSACHUSETTS

WORK HOLDER FOR GRINDING MACHINES

Application filed August 8, 1929. Serial No. 384,339.

This invention relates to means for holding pieces of work in a grinding machine or other similar machine tool.

It is the general object of my invention to provide an improved holder for such purposes by which three or more pieces of work may be engaged and held in an accurately centered position for a grinding or other similar operation.

10 A further object is to provide means by which each of several pieces of work will be independently centered but in which all of the pieces are firmly secured and held during the machine operations thereon.

15 My invention further relates to arrangements and combinations of parts which will be hereinafter described and more particularly pointed out in the appended claims.

20 A preferred form of the invention is shown in the drawings in which

Fig. 1 is an end elevation of parts of a grinding machine embodying my improvements;

25 Fig. 2 is a sectional side elevation, taken along the line 2—2 in Fig. 1;

Fig. 3 is an end view of my improved work-holder looking in the direction of the arrow 3 in Fig. 4;

30 Fig. 4 is a side elevation thereof; and

Fig. 5 is a detail view, to be described.

Referring to the drawings, I have shown a plate 20 adapted to be secured to the end of a large hollow rotatable work spindle 21 suitably mounted in a grinding machine. The plate 20 is provided with an outwardly projecting hub portion 23 within which a bushing 24 is closely fitted. The bushing 24 has an external flange 25 at its outer end engaging a shoulder 26 on the inside of the hub 23.

40 At its inner end, the bushing 24 has an internal flange 27 adapted to be engaged by the innermost piece of work W in a work holder 30 to be described.

This work holder 30 is slidable in the bushing 24 and is provided with a flange 31 near the middle of its length which is cut away or slotted, as indicated at 32 (Fig. 3) at the opposite ends of one diameter to receive dogs 33 mounted on a clamping member 35. The 50 member 35 is slidable on the outer surface of

the hub 23 and is provided with a plurality of springs 36 acting to force the clamping member 35 yieldingly toward the supporting plate.

A rock shaft 40 is mounted on the frame of the machine and is provided with depending arms 41 having yoke members 42 adapted to engage the clamping member behind an outer flange 44 thereof. The shaft 40 may be manually rocked to push the clamping member 60 outward against the tension of the springs 36.

When inserting the work holder in the machine, the clamping member is first moved outward, after which the work holder 30 is inserted, with the notches 32 in alignment 65 with the dogs 33. After the notched flange 31 has passed the dogs 33, the work-holder is turned so that the dogs will engage the flange 31, after which the rock shaft is released and the springs 36 force the work-holder yieldingly into the bushing 24.

70 My improved work-holder 30, as shown in the drawings, is designed for centering and holding three pieces of work W, W' and W², which are shown as being in the form of ball 75 races for anti-friction bearings. These ball races as they come to the grinding machine are not very accurate in their external diameters and are also not commonly of exactly circular cross section.

75 In order that these slightly rough and irregular articles may be separately and accurately centered in the work-holder, I provide a plurality of work-engaging springs 60 and 61. These springs are of double-end 80 construction, as indicated in Figs. 2 and 5, and are secured on the inside of the work-holder 30 in alternate arrangement.

85 Reference to Fig. 2 will show that the spring 60 engage the two outer pieces of work W' and W² while the springs 61 engage the inner and outer pieces W and W. The springs 60 and 61 yield slightly to accommodate slight variations in diameter and in accuracy of cross section, but all of the 90 springs co-operate to bring each inserted piece of work independently to an averaged centered position.

95 The pieces of work are assembled in the holder 30 before the holder is placed in the 100

machine and the outermost piece W^2 engages a shoulder 75 on the inside of the holder 30.

After the three pieces of work are placed in the holder and are centered by the springs 60 and 61 thereof, the holder is placed in the machine and the innermost piece of work W engages the flange 27 previously described.

The springs 36, acting through the clamping member 35 and dogs 33, place substantial pressure on the pieces of work W , W' and W^2 and clamp the same firmly between the shoulders or flanges 27 and 75. The work is thus accurately held during the grinding operation and the operator in the meantime loads additional work-holders so that when the grinding on one lot is completed the work may be removed and replaced with a minimum loss of time.

While I have shown my improved work-holder as providing for the centering of three pieces of work, it will be evident that the invention can be readily extended to provide similar means for centering additional pieces.

Having thus described my invention and the advantages thereof, I do not wish to be limited to the details herein disclosed, otherwise than as set forth in the claims, but what I claim is:

1. In a machine tool, a holder for cylindrical work comprising a hollow cylindrical sleeve having an internal flange, a hub member in which said sleeve is centered and supported, means engaging said sleeve for yieldingly seating said sleeve in said hub member and thereby clamping a plurality of work pieces between the internal flange of said sleeve and a shoulder fixed with respect to said hub member, and means to center the work pieces in the cylindrical sleeve, said means comprising springs mounted on the inner face of said cylindrical sleeve and yieldingly engaging the outer walls of said work pieces.

2. In a machine tool, a holder for cylindrical work comprising a hollow cylindrical sleeve having an internal flange, a hub member in which said sleeve is centered and supported, means engaging said sleeve for yieldingly seating said sleeve in said hub member and thereby clamping a plurality of work pieces between the internal flange of said sleeve and a shoulder fixed with respect to said hub member, and means to center the work pieces in the cylindrical sleeve, said means comprising a plurality of axially extended double-ended springs, each spring engaging the outer face of one piece of work with one end of said spring and the outer face of another piece of work with the other end of said spring.

3. The combination in a work holder as set forth in claim 2, in which the springs are of different lengths, the shorter springs engaging and centering two adjacent pieces

of work and the longer springs engaging and centering spaced work pieces.

4. The combination in a work holder as set forth in claim 2, in which the springs are of different lengths, the shorter springs engaging and centering two adjacent pieces of work and the longer springs engaging and centering spaced work pieces, said longer and shorter springs being alternately arranged about the inner cylindrical surface of said sleeve.

5. The combination in a work holder as set forth in claim 2, in which each double ended spring is secured to said sleeve at an intermediate point in the length of said spring, while the ends of said spring are free to move radially for a limited distance.

In testimony whereof I have hereunto affixed my signature.

ALDEN M. DRAKE.
